TOOTHBRUSH AND TOOTHBRUSH ATTACH-MENTS

Dieter Rams, Koenigstein, Taunus, and Juergen Greubel, Eschenhahn, Germany, assignors to Braun Aktiengesell-schaft, Frankfurt am Main, Germany

Filed Nov. 5, 1969, Ser. No. 19,952
Claims priority, application Germany May 9, 1969

Term of patent 14 years

Int. Cl. D6—01

U.S. Cl. D33—28

FIG. 1

FIG. 3

FIG. 1 is a perspective front view of this combined holder for an electrical toothbrush and toothbrush attachments showing our new design;

FIG. 2 is a top plan view thereof;

FIG. 3 is a side elevational view thereof; and

FIG. 4 is a bottom plan view thereof.

We claim:

The ornamental design for a combined holder for an electrical toothbrush and toothbrush attachments, substantially as shown.
